Primary Examiner — Jonathan J Han*Assistant Examiner* — Sharon H Schwartz(74) *Attorney, Agent, or Firm* — ArentFox Schiff LLP(57) **CLAIM**

The ornamental design for a shoe, as shown and described.

DESCRIPTION

FIG. 1 is a front rear perspective view of a shoe showing our new design;

FIG. 2 is a front view of the design shown in FIG. 1;

FIG. 3 is rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

Colors form no part of the claimed design. Broken lines are included for the purpose of illustrating portions of the shoe that form no part of the claimed design.
